UNITED STATES PATENT OFFICE.

JACOB KURTZ, OF DELANO, MINNESOTA.

WHIFFLETREE ATTACHMENT.

SPECIFICATION forming part of Letters Patent No. 290,890, dated December 25, 1882.

Application filed October 13, 1883. (No model.)

To all whom it may concern:

Be it known that I, JACOB KURTZ, a citizen of the United States of America, residing at Delano, in the county of Wright and State 5 of Minnesota, have invented certain new and useful Improvements in Attachments for Whiffletrees; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to devices for detaching horses from vehicles to which they are hitched; and my invention consists in the improved construction, as will be fully described hereinafter, whereby the detaching of the animal is at all times within the control of the driver, the accidental detachment prevented, and the devices for preventing such accidental detachment so arranged as to be thrown into or out of engagement with the 20 working parts of the device.

In the accompanying drawings, Figure 1 is a perspective view of a whiffletree having my invention embodied therein and arranged to hold the traces; Fig. 2, a like view, showing the manner of detaching the traces; and Fig. 3 is a front view of the levers.

A represents a whiffletree provided with the caps *a a* at its ends, having ears *b* perforated for the passage of the bar *B*, the ends *c* of 35 which are bent, as shown, so that when turned toward projections *d*, located on the ends of the whiffletree, they can hold the ends of the traces without any liability of the detachment of the traces, unless the said bent ends *c* be 40 turned away from the projections *d*. The bar *B* is centrally supported by perforated ears *e* of a plate, *C*, which embraces the lower angular edge, *f*, of the whiffletree, said plate being secured rigidly in position by means of securing-screws *g*, a bolt, *D*, passing vertically 45 through the plate *C*, through the whiffletree, and through a bearing-plate, *E*, on the top thereof, which carries integrally at its upper end a bearing-bracket, *F*, the withdrawal of

said bolt being prevented by means of a nut 50 engaging the lower threaded end of the bolt. A bell-crank lever, *G*, pivoted in the bracket *F*, has one of its ends connected by a chain, *h*, to the looped end *i* of an arm, *H*, which turns on the rod *B*, but is prevented from becoming laterally displaced by means of fixed collars *j* rigidly secured to the rod *B* at each side of said arm *H*. The portion *k* of said arm, which turns on said rod *B*, is cam-shaped, so that when said arm *H* is in the 55 position shown in Fig. 1 its cam portion *k* will be out of a recess, *l*, therefor in the face of the whiffletree, and permit a lug, *m*, on a pivoted arm, *I*, to enter behind a second arm, *J*, which is rigidly hung on the rod *B* and 60 turns with said rod, its point of connection with the same being also in the shape of a cam, the cam wedging against the lug *m* and preventing any movement of said arm *J* upward from its dependent position illustrated 65 in Fig. 1. An ear, *n*, on the arm *I* rests upon the cam portion of the arm *H*, so as to be lifted thereby when the said arm *H* is lifted, this movement raising the entire pivoted arm *I* on its pivot and lifting its lug *m* from behind 70 the cam portion of the arm *J*, thereby permitting said arm to be lifted, and thus rotate the rod *B* and turn its bent ends *c*, so that the traces can slip out of engagement therewith. This position of the parts is fully illustrated 75 in Fig. 2. A strap, *K*, passes through a loop, *o*, on the arm *J*, through a ring, *O*, connected by a chain, *h h*, to the end *i* of the lever, a strap, *L*, connected to the ring *O*, and passing up to the driver's seat, permitting the driver 80 to pull the strap and throw all the parts into the position illustrated in Fig. 2.

From the foregoing description it will be apparent that the device is simple and effective in operation, and of cheap and durable 85 construction.

I claim—

1. The combination, in a horse-detaching device, of a bar turning in bearings on the whiffletree, the ends being bent to engage the 90 ends of the traces, and an arm turning loosely on the bar to disengage a locking device and permit a second arm to be lifted, and thereby

rotate the bar to turn the bent ends thereof and effect the disengagement of the traces, substantially as set forth.

2. The combination, in a horse-detaching device, of a bar, B, having the bent ends c, arms H, I, J, arranged as described, and bell-crank lever connected therewith by chains and strap-connections, as specified, and a strap-connection for manipulating the said

bell-crank lever and the arms, substantially as set forth.

In testimony whereof I affix my signature in presence of two witnesses.

JACOB KURTZ.
